UNITED STATES PATENT OFFICE.

FREDERICK C. SCHOFIELD, OF LYNCHBURG, VIRGINIA, ASSIGNOR TO TOBACCO STEMMING MACHINE COMPANY, OF LYNCHBURG, VIRGINIA, A CORPORATION OF DELAWARE.

ART OF STEMMING TOBACCO.

Application filed December 10, 1921. Serial No. 521,319.

To all whom it may concern:

Be it known that I, FREDERICK C. SCHOFIELD, a citizen of the United States, and resident of Lynchburg, in the county of Campbell and State of Virginia, have invented certain new and useful Improvements in the Art of Stemming Tobacco, of which the following is a specification.

This invention relates to leaf stemming and more particularly to a method of and apparatus for stemming tobacco leaves; and has special reference to the provision of a leaf stemming method and apparatus of the type in which the web or lamina of the leaf is detached from the stem by stripping the leaf lamina from an intermediate point of the stem towards its opposite ends.

One of the common classes of machines used for stemming tobacco leaves comprises apparatus in which the principle is employed of seizing or gripping the stem of the tobacco leaf and stripping the web or lamina of the leaf from the stem as by drawing the gripped leaf through stemming or stripping elements. According to one type of machine employing this general principle, the leaf is seized or gripped at the butt end of the same and the leaf so gripped is fed through stemming elements which strip the lamina from the butt end towards the tip end of the leaf. Although in this type of machine the butt, being strong, tough and firm, may be securely gripped and the leaf efficiently fed through the stemming elements, it is well known that the detaching of the lamina from the stem is carried on with considerable difficulty, the stemming from butt to tip being with the grain of the leaf and in causing a crowding or bunching of the lamina about the stem being a fairly difficult operation. To overcome this disadvantage incident to stemming from butt to tip another type of machine has been devised in which the leaf is gripped or seized at the tip end and the stemming operation effected from the tip towards the butt. The stemming or stripping from tip towards butt involves a stripping against the leaf grain and such stripping may be effected with considerable ease and facility. However, in the latter type of machine, although the stripping step may be carried on to advantage, considerable

difficulty has been encountered in properly gripping the tip end of the leaf and feeding the leaf from the stemming elements by the gripped tip end, the thin relatively frail and infirm tip end of the leaf being liable to tearing and breaking when subjected to a moderate degree of pulling strain. This disadvantage has been so serious at times that in some forms of this latter type of machine special means have had to be devised for changing the gripping point of the stem from the tip towards the tougher part of the stem fibre as the leaf is progressively stripped therefrom. The type of machine, therefore, where the butt end of the leaf is seized and the leaf stripped from butt to tip is open to the disadvantage of difficult stripping or stemming; and the type where the tip end is gripped and the leaf stripped from the tip to butt is open to the equally serious disadvantage of insecure and imperfect gripping and feeding.

To eliminate the defects or disadvantages incident to such types of machines and to combine the desirable features thereof, a third type of machine has been devised in which the leaf stem is gripped at a point intermediate the ends thereof and the lamina stripped from such point towards the opposite ends of the leaf. The intermediate point of the stem consists of a relatively tough fibre and such part of the stem may be securely taken hold of and the leaf may be fed through stripping means with the stem so gripped without the liability of the stem breaking or tearing. Although part of the stemming, namely that from the gripped intermediate point towards the tip, is relatively difficult, the stemming from the gripped intermediate point towards the butt is carried on with ease. In this manner relatively facile stripping or stemming may be combined with efficient gripping and feeding operations.

Although this third type of stemming machine offers a way for generally eliminating the defects and for combining the advantages of the other machines in the class above referred to, prior machines of this last type have not been found to work with the consistency, ease and speed desired in the stemming art. Where the parts of the leaf on opposite sides of the intermediate

point were stripped in successive steps, special gripping, feeding and stemming constructions had to be devised which were at once cumbersome in structure and intricate in operation. Where the parts of the leaf were stripped in opposite direction simultaneously from the intermediate point, in addition to providing several sets of stemming rolls active on such parts with the resulting increase in complexity of the machine structure, special means for gripping the stem so as to take up for differential strains in opposite directions had to be incorporated in the machine because of the necessity to equalize stripping action in opposite directions, this being impossible of attainment without such means because of the fact that stripping in the direction towards the butt requires less resisting pull than stripping in the direction towards the stem, the draws in opposite direction being therefore unequal. Prior machines of this type, therefore, although logically correct in attacking the stemming problem on the broad principle of gripping at an intermediate point and stemming towards the opposite ends of the leaf, do not supply the best solution from the viewpoint of accomplishing the desired ends with relatively simple apparatus so that gripping, feeding and stemming can be carried on with the facility and speed attainable in this type of machine.

My present invention primarily contemplates the provision of an apparatus of the type last referred to in which the principle of gripping the stem at a point intermediate its ends and stripping the lamina or blade of the leaf from such point towards the opposite ends of the leaf is employed, my invention contemplating a novel method of and apparatus for gripping, feeding and stemming the blades, such method and apparatus not being subject to the defects found in prior machines of this type.

The principal objects of my invention may be said to include, besides the provision of a method of and apparatus for stemming tobacco leaves of the kind referred to, the provision of a method and apparatus in which the leaf is folded about the gripped point and the lamina detached from the resulting folds; the provision of a method and apparatus of this type in which the leaf is folded and fed in folded condition through a set of stemming elements, the folds of the leaf being simultaneously acted upon by the same set of stemming rolls, the apparatus required being relatively not only simple, but stemming being carried on with a tendency towards equalizing opposing pulls or draws on the stem and with secure stem gripping and feeding effected; the still further provision of a method and apparatus in which the lamina

of the leaf is removed from the folds and from the gripped portion of the stem, the latter being effected by secondary stemming elements; the further provision of novel secondary stemming elements; the still further provision of a novel method and means for positioning the tobacco leaves and for feeding the grippers thereto and the general provision of simple, easily operated and controlled apparatus carrying on the various steps of the method.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention and in which:

Figure 1 is a side elevational view of my stemming machine with parts broken away to show the construction of the feeding and stemming apparatus including the primary and secondary stemming elements.

Figures 2 to 5 are views showing successive stages of the stemming operation,

Figure 6 is a detached view of the secondary stemming elements showing the same in a stage of activity subsequent to that shown in Figure 1.

Figure 7 is a rear end elevational view of the secondary stemming elements, and

Figure 8 is a view of a detail.

As hereinbefore referred to, a prime desideratum of my present invention comprehends the provision of a tobacco stemming construction in which the tobacco leaves are folded about a point intermediate the ends of the leaf and the lamina or web of the leaf is stripped from the resulting folds. In the present exemplification of my invention the tobacco leaves, after being untied from the bundle or "hand," are placed on a feed table and while in position on said table the leaves are seized or taken hold of by means of gripping elements fed to the table, the leaves being gripped at a point or portion intermediate the ends of the leaf and the so gripped leaves are fed forward to be stemmed. This exemplification of my invention is shown in the drawings and referring to Figure 1 of the drawings, I show mounted on a bracket 10 forming part of the stationary framework 11 a support 12; and on the said support I provide the inclined feed table 13. Upon the table 13 are placed the individual leaves which are untied from a "hand," the leaves being positioned on the table so as to be capable of being seized by gripping means active on a point of the stem intermediate the ends thereof. To this end the table 13 is provided with a section or portion 14 lying below the path of the grippers, as will appear

presently, and connected to the said section 14 I provide a gauge board 15 functioning to aline the butts of the leaves, the said gauge board 15 being adjustably connected 5 to the table section 14 as by means of the slot and wing nut means 16, the adjustability of the gauge board 15 being provided to the end of adapting the machine to various lengths of tobacco leaves. The leaves L are 10 placed on the table with the butts preferably alined by the gauge board 15, as clearly shown in Figure 1 of the drawings, the intermediate portion of the leaves being located in the space between the table 13 and 15 its extended section 14.

To the end of providing means for gripping the leaves and for feeding them forwardly, I preferably provide a feeding apparatus of the type shown in my prior 20 Patents Nos. 1,268,392 of June 4, 1918, and 1,286,124 of November 26, 1918, the said feeding means comprising generally endless companion carriers of the sprocket chain type, the said sprocket chains carrying complementary gripping bars for seizing and feeding the leaves through the stemming apparatus. Referring to Figure 1 of the drawings, I show the sets of companion sprocket chains, one set being shown in the 30 drawings and designated as 17 and 18 respectively, the said sprocket chains being trained over opposed sprocket gears 19, 20, 21 and 22 respectively. The sprocket gears 19 to 22 are suitably journaled in bracketed 35 structures 23 and 24 forming part of the stationary framework 11 of the machine, the sprocket gears being positively actuated to be movable in synchronism by any desirable mechanism.

40 Spacedly mounted in the sprocket chains 17 and 18 I provide sets of complementary gripping elements in the form of gripping bars, the said gripping bars being fed into coacting clamping condition for gripping 45 and feeding the tobacco leaves. This is clearly shown in Figure 1 of the drawings, wherein is shown provided a series of spaced carrier bars 25 on the chain 18 and a series of complementary clamping bars 26 on the 50 endless chain 17. As the companion endless chains are rotated by the synchronously operated sprocket gears, the complementary endless gripper bars 25 and 26 are fed into coacting condition, as clearly shown to the 55 left of Figure 1, the gripper bars 25 and 26 gripping therebetween the leaves L at a region intermediate the ends of the leaves, the leaves so gripped being then fed from the feed table 13 forwardly for the stemming operation with both ends of the leaf drooping, as clearly shown in Figure 1 of the 60 drawings.

The leaves after being gripped and fed forward in the manner hereinabove referred 65 to, are then forwarded and the lamina or

web of the leaves is stripped from the resulting folds. For the purpose of folding the leaves any suitable means may be provided and I prefer, as shown in the present exemplification of my invention, to fold the 70 leaves by the act of feeding the same through the stemming elements, the drooping forward end of the leaf facilitating the folding step. Referring again to Figure 1 of the drawings, I show the provision of stemming 75 elements such as the opposed stemming rolls 27 and 28, these stemming rolls being preferably of the type surfaced with card clothing, the stemming rolls 27 and 28 being suitably journaled in the oscillatable arms 80 29 and 30 respectively. The arm 29 is suitably journaled in the framework of the machine and the arm 30 is journaled in the bracketed structure 31 forming part of the frame 11 of the machine, such a construction being fully shown in my Patent No. 1,268,392 of June 4, 1918. The arms 29 and 30 may be provided with adjustable tensioning elements as shown in my said patent for the purpose of adjusting the 90 stemming action of the said rolls. The tobacco leaves gripped between a carrier bar 25 and a clamping bar 26 are fed by the endless chains to and between the card clothing rolls 27 and 28, these rolls separating under tension to permit the leaves to pass therebetween, the advance or butt end of the leaf being lapped or folded under the rear end of the leaf by the act of feeding the said leaf between the stemming rolls. 95 The separation of the stemming rolls 27 and 28 and the folding of the leaf therebetween is clearly shown in Figure 2 of the drawings. In the onward movement of the gripping bars 25 and 26 after the latter 105 pass the stemming rolls 27 and 28, the stemming rolls close upon the tobacco leaves as clearly shown in Figure 3 of the drawings, the stripping action of the said stemming rolls commencing at such time. The bars 110 25 and 26 are given preferably a pear shaped configuration as shown in the drawings, to the end that the rolls 27 and 28 close for stemming activity immediately the said bars pass from underneath the rolls. The 115 rolls 27 and 28 are rotated in opposite directions as indicated by the arrows in the figures, suitable means being provided and connected to the other operating parts of the apparatus for imparting the desired rotation to the stemming rolls. With the feeding forward of the bars and the rotation of the stemming rolls 27 and 28, the lamina or web of the leaf L is stripped from the 120 overlying folds of the leaf, the coacting movement between the gripping bars and the rolls effecting a sluffing or wiping stripping action on the leaf web, the relative movement of the parts of the apparatus 125 effecting a simultaneous stripping or de- 130

taching of the folds of the leaf from the stem, as clearly indicated in Figure 4 of the drawings. Figure 5 shows the stage of operation after the lamina has been removed 5 from the overlying folds of the leaf, the stem S being shown held between the bars 25 and 26 with the lamina stripped therefrom except for a part of the lamina at the gripping bars which remains attached to the 10 leaf and which is stripped in a subsequent operation, as will appear more in detail hereinafter.

For the purpose of effecting a secure gripping of the bars 25 and 26 as the same are 15 passed between the stripping rolls 27 and 28, I may provide the opposing pressure shoes 32 and 33 acting on complementary bights or reaches of the companion chains 17 and 18, the shoe 32 being preferably stationarily mounted on the framework of the 20 machine and the shoe 33 being yieldingly mounted on the same, the said shoe 33 being resiliently mounted for yielding movement by means of the adjustable spring pressure 25 elements 34 and 35 connecting opposite ends of the shoe 33 to upstanding bearings 36 and 37 respectively, the latter forming part of the framework of the machine.

I have found in the practice of the method 30 carried out by the above described apparatus, that the tobacco leaves may be folded about an intermediate point without breaking or snapping and that the leaf when so folded may be effectively stemmed by the 35 simple stripping apparatus hereinabove described. I have further found that by this method and means the stem may be securely gripped at a relatively tough portion thereof, and that when the leaf is folded about the 40 gripped point and more particularly about the complementary grippers with the lamina simultaneously stripped in the same direction by the opposing stemming rolls, that the tendency for the leaf and the stems to 45 slip between the gripping bars during stripping action is effectively minimized with the resulting increase in stemming efficiency, the simultaneous action of the stripping rolls on the overlapping folds furthermore tending 50 to equalize the pulling strains on the opposite folds, this being another factor in preventing slipping of the stems between the gripper bars. With my method and apparatus, furthermore, the leaves L may 55 be fed to the table 13 without that degree of accuracy hitherto found necessary in prior machines where the alining of the butts involved the need for care and accuracy of feeding of the stems to the gripper 60 elements, the leaves when in fact fed indiscriminately on the table 13 in my invention being properly taken hold of at some intermediate point by the gripping bars 25 and 26. In prior machines where the butts 65 of the leaves are gripped and fed forwardly,

the improper positioning of the leaves on the table oftentimes results in a decreased productivity or yield of the apparatus for the reason that such improper feeding results in improper gripping by the bars, thus yielding a high percentage of "drops" and also resulting at times in missing the leaves and failing to feed them at all. In the practice of my method, furthermore, it is unnecessary to preliminarily strip the leaf from the butt 75 ends, preliminary butting apparatus being thereby eliminated. Moreover, with the apparatus I provide, the leaves are fed in a simple manner through a set of stemming elements, the law of operation of the machine being relatively simple with the resulting yielding of more consistent and uniform results.

To the end of preventing the folding of the leaf L about an intermediate point from 80 causing the stem at such point to snap or break, the carrier bar about which the leaf is folded is preferably so contoured as to prevent the undue flexing of the stem to the breaking point. To this end the bar is convexed as shown in the figures of the drawings, Figure 8 of the drawings showing particularly one form in which my complementary bars may be made. Referring to this figure the upper clamping bar 26' is squared 85 at the advancing side as shown at 38, the lower or carrier bar 25' being shown rounded or convexed as at 39, both bars being shown rounded or convexed as at 39, both bars being shown dished as at 40 and 41 to permit the 100 stemming rolls to close immediately the bars pass from between the same. The bars 25' and 26' may also be provided with complementary corrugated or sinusoidal gripping surfaces, as shown at 42 and 43 respectively. 105

In the feeding of the leaves through the stripping elements 27 and 28, the leaves may be completely stripped so as to effect stripping in a single operation, as shown in my co-pending application, Serial No. 521,320, 110 filed December 10, 1921, or the leaves after the lamina is stripped from the folds thereof may be fed for a subsequent stripping operation to detach that portion of the web or lamina adhering to the stem adjacent the 115 gripped point thereof, the present exemplification of my invention comprehending a construction in which a secondary stripping action operative to remove the remaining portion of the web is provided. 120 This is shown in Figures 1, 6 and 7 of the drawings, and referring more particularly to Figure 1 of the drawings, I show means for feeding the primarily stripped stem through secondary stripping or stemming 125 elements. To this end I provide, preferably journaled in the bracket 24, a rotating brush element 44 rotating clockwise as viewed in Figure 1 and as indicated by the arrow, the said brush element being active 130

on the forward or butt end of the stem to throw the same upwardly so that the butt end of the stem may glide or slide over a table 45, which also may be journaled in the bracket structure 24. After moving over the table 45 the butt end of the stem S is received between and gripped by the opposed stemming rolls 46 and 47, these stemming rolls being similar in construction to the primary 10 stemming rolls 27 and 28 and providing a surface with card clothing or the like, the said stemming rolls being rotated at a peripheral speed substantially equal to the rectilinear speed of the feed chains 17 and 15 18 and the gripper bars 25 and 26. The stemming rolls 46 and 47 rotate as indicated by the arrows in Figure 1, the rolls always rotating in the same direction and functioning first to forward the stem received 20 from the gripper bars 25 and 26 and functioning subsequently, as will appear presently, for stemming or stripping the remaining lamina from the stem. Located in advance of the secondary stemming rolls 46 and 47 and also suitably journaled in the bracketed structure 24 I provide the opposed drawing rolls 48 and 49, the drawing roll 48 being journaled for rotation and the drawing roll 49 being journaled for rotation 25 and for yielding movement to and from the drawing roll 48. For the purpose of yieldingly mounted the drawing roll 49 I may provide the journal block 50 slidable in suitable ways 51 forming part of the bracketed structure 24, an adjustable tensioning means 52 being provided for resiliently urging the journal block 50 and the roll 49 into coacting relation with the drawing roll 48. The drawing rolls 48 and 49 are rotated in the directions indicated by the arrows in Figure 1, these drawing rolls functioning to receive the stem S from the stemming rolls 46 and 47 and for moving the same forwardly. The drawing rolls 48 and 49, however, rotate at a speed greater than the speed of rotation of the stemming rolls 46 and 47, and when the stem S is received between the drawing rolls 48 and 49, the stem being released at this time by the gripping bars, is rapidly 40 pulled through the stemming rolls 46 and 47 with the result that the stemming rolls now functioning for the purpose of stripping the remaining attached lamina from the stem S, this stage of operation being particularly shown in Figure 6 of the drawings, the resulting lamina being detached in flakes and falling into the receptacle 53 provided therefor, the completely stripped stems after being drawn by the drawing rolls 48 and 49 45 dropping into the adjacent receptacle 54.

For the purpose of allowing the carrier bars 25 to move past the table 45 the said table is preferably pivotally mounted as shown at 57 and is weighted at 58 to the end of permitting the table 45 to resume its

horizontal position after a carrier bar 25 has passed the same.

For the purpose of keeping the stemming rolls 46 and 47 free from any tobacco web, I preferably provide the cleaning blade 70 structures 55 and 56 rotating with respect to the stemming rolls 46 and 47 as indicated by the arrows, the said blade construction being shown in my Patent No. 1,207,085 of December 5, 1916. The cleaning or clearing blades 55 and 56 may be actuated from the stemming rolls 46 and 47 and referring especially to Figure 7 of the drawings, I show the said clearing blades 55 and 56 mounted on the shafts 59 and 60, the said shafts being suitably journaled in the brackets 24, the shafts being provided at one end with the pinions 61 and 62 respectively meshing with the gears 63 and 64 respectively. The gear 64 may be connected to the shaft 65 of the stemming roll 47 and the gear 63 may be suitably journaled in a bracket support 66 attached to one of the brackets 24. Each of the gears may be connected to be operated by suitable chain drives, gear 64 being connected for operation by drive chain 67, the gear 63 being driven by drive chain 68. For the purpose of driving the stemming roll 46 synchronously with the stemming roll 47, the roll 46 may be driven from the roll 47 and to this end the shaft 69 carrying the roll 46 is provided with the gear 70 and the shaft 65 carrying the roll 47 is provided with the gear 71 meshing with the gear 70.

The practice of my method and the operation of my apparatus will, in the main, be apparent from the above detailed description thereof. The leaves L, after being untied from the bundle or "hand," are placed on the table 13 and table section 14 with the butts of the leaves preferably aligned by the gauge board 15. The leaves positioned in this manner are then gripped at a point intermediate the ends thereof between the gripper bars 25 and 26 with the leaves then fed forwardly. As the leaves are advanced by the gripper bars the leaves are fed between the stemming rolls 27 and 28, the stemming rolls functioning to fold the advance portions of the leaves under the remaining portions of the leaves, the leaves so folded being then fed through the stripping rolls 27 and 28 for the first or primary stemming operation. The leaves are securely gripped by means of the gripping bars 25 and 26, the gripping being sufficient to overcome the opposing pulls exerted on the stem by the stripping rolls, the stripping rolls in being operative simultaneously on opposite folds of the leaf tending to equalize the opposing pulls. After the lamina of the leaf is stripped from the folds, the stem with the lamina adjacent the gripped portion of the stem is fed forwardly and is op-

erated upon by the secondary stripping elements 46 and 47 for reclaiming or salvaging the remaining adhering portions of the web.

From the above it will be apparent that I have provided an apparatus in which the leaves may be effectively gripped at an intermediate point and efficiently fed for the stripping step, the stripping apparatus being of relatively simple construction and the cooperation of the feeding and stripping means being such as to permit of high speed of operation, efficient stemming, and easy control by an operator.

While I have shown my device in the preferred form, it will be obvious that many changes and modifications may be made in the structure disclosed without departing from the spirit of the invention, defined in the following claims.

20 I claim:

1. The method of leaf stemming which consists in gripping the leaf stem at a point intermediate its ends, in folding the leaf and in removing the lamina portions of the leaf from the folds.

2. The method of leaf stemming which consists in gripping the leaf stem at a portion intermediate its ends, in folding the leaf, in removing the lamina portions of the leaf from the folds and in removing the lamina from said gripped stem portion.

3. The method of leaf stemming which consists in gripping the leaf stem at a point intermediate its ends, in folding the leaf and in removing the lamina portions of the leaf from the folds by drawing the same through stemming or stripping elements.

4. The method of leaf stemming which consists in gripping the leaf stem at a point intermediate its ends and in stripping the lamina portions of the leaf from such point towards the ends of the leaf by drawing the gripped leaf through a single set of stemming elements operating to strip both ends.

5. The method of leaf stemming which consists in gripping the leaf stem at a portion intermediate its ends, in folding the leaf, in removing the lamina portions of the leaf from the folds by drawing the same through stemming elements and in then removing the lamina from the gripped portion of said stem.

6. The method of leaf stemming which consists in gripping the leaf stem at a portion intermediate its ends, in stripping the lamina portions of the leaf from such point towards the ends of the leaf by drawing the gripped leaf through a single set of stemming elements operating to strip both ends and in then drawing the stem through another set of stemming elements to remove the lamina from said gripped stem portion.

7. The method of stemming tobacco, which comprises folding the leaf at a point

intermediate its ends, and stripping the laminae from the fold towards the ends of the leaf.

8. The steps in the process of stemming leaves which consist in folding the leaf about a point intermediate its ends and in removing the lamina from the resulting folds.

9. An apparatus for stemming leaves, comprising means for effecting a gripping of the leaf stem at a point intermediate its ends whereby the leaf may be folded and means for stemming the leaf in folded condition.

10. An apparatus for stemming leaves comprising means for effecting a gripping of the leaf stem at a point intermediate its ends whereby the leaf may be fed in folded condition, stemming elements and means for feeding the folded leaf through the stemming elements.

11. An apparatus for stemming leaves, comprising means for effecting a gripping of the leaf stem at a point intermediate its ends whereby the leaf may be folded and means for stemming the leaf in folded condition, the gripping means comprising a gripping bar convexed at the advance end to permit folding of the leaf without breaking the stem thereof.

12. In an apparatus for stemming leaves, a gripping means comprising a gripping bar convexed at the advance end to permit folding of the leaf about the said bar without breaking the stem thereof.

13. An apparatus for leaf stemming comprising means for effecting a gripping of the leaf stem at a point intermediate its ends whereby the leaf may be folded, means for stemming the lamina from the resulting leaf folds and means for stemming the lamina from the gripped portion of the stem.

14. An apparatus for leaf stemming comprising means for effecting a gripping of the leaf stem at a portion intermediate its ends whereby the leaf may be folded and means for removing the lamina from the leaf folds and from the gripped stem portion.

15. An apparatus for stemming leaves comprising means for effecting a gripping of the leaf stem at a portion intermediate its ends whereby the leaf may be fed in folded condition, primary stemming elements and means for feeding the folded leaf through the primary stemming elements to remove the lamina from the folds, secondary stemming elements and means for feeding the stem through the secondary stemming elements to remove the lamina from the gripped stem portion.

16. An apparatus for stemming tobacco comprising means for effecting a gripping of the leaf at a point intermediate its ends

- and feeding the same so gripped through stemming elements; the stemming elements functioning to fold the leaf and to strip the lamina from the resulting folds.
- 5 17. In an apparatus for stemming tobacco, a gripper means, means for feeding the gripper means, a feed table for tobacco leaves arranged to intersect the path of movement of the gripper means, the arrangement being such that the moving gripper means will take hold of a tobacco leaf on the feed table at a point intermediate the ends thereof.
- 10 18. In an apparatus for stemming tobacco, complementary endless chain feeding means, companion gripper bars carried by the chain feeding means, a tobacco feed table associated with the feeding means, the said feed table comprising a gauge board intersecting the path of movement of the gripper bars, the construction being such that the tobacco leaf on the gauge board is gripped by the bars at a point intermediate the ends thereof.
- 15 19. An apparatus for stemming leaves comprising means for gripping the leaf stem at a point intermediate its ends whereby the leaf may be fed in folded condition, plurality of relatively movable stemming rolls 20 having their axes in a vertical plane and means for feeding the folded leaf through the stemming rolls, the gripping means comprising a plurality of gripping bars between which the leaf stem is held, one of the bars 25 being convexed at the advance end thereof.
20. In an apparatus for stemming tobacco, means for effecting the gripping of the stem at a point intermediate the ends thereof and for feeding the stem forward so gripped, stemming elements, means active on the 40 advance end of the stem for directing the said end to the stemming elements; the stemming elements being operative to feed the stem forward and drawing means receiving the stem from the stemming elements 45 and operative to draw the same through the stemming elements.
21. In an apparatus for stemming tobacco, means for effecting the gripping of the stem at a point intermediate the ends thereof and 50 for feeding the same forward so gripped, stemming rolls, means active on the advance end of the stem for directing the said end to the stemming rolls, the said means including a rotary brush, the stemming rolls 55 being operative to feed the stem forward and drawing rolls receiving the stem from the stemming rolls and operative to draw the same through the said stemming rolls.
22. The method of simultaneously 60 stripping the laminae from a point intermediate the ends of a tobacco leaf toward both ends with a single stripping device, which comprises folding the leaf, and drawing it through the stripping device in folded 65 condition.

Signed at Lynchburg, in the county of Campbell and State of Virginia, this 6th day of December A. D., 1921.

FREDERICK C. SCHOFIELD.
